D. MELLOR

FURNACE GRATE BAR CONSTRUCTION

Filed April 23, 1925

Inventor

Dennis Mellor,

Robert M. Barr,

Attorney

UNITED STATES PATENT OFFICE.

DENNIS MELLOR, OF PHILADELPHIA, PENNSYLVANIA, ASSIGNOR OF ONE-HALF TO
ALEXANDER GALE, OF PHILADELPHIA, PENNSYLVANIA.

FURNACE-GRAVE-BAR CONSTRUCTION.

Application filed April 23, 1925. Serial No. 25,324.

The present invention relates to the promotion of combustion of fuel in furnaces and more particularly to an improved grate bar structure.

5 Some of the objects of the present invention are to provide a grate bar construction whereby the entering air is so proportioned as to produce perfect and complete combustion of the gases in a furnace; to provide 10 a furnace structure wherein the discharge of smoke is eliminated; to provide a grate structure which increases the combustion area of a furnace so that better diffusion and chemical combination of the gases, air 15 and smoke take place before leaving the furnace; to provide a grate bar which is arranged to deliver air at the front of the bridge wall to mix with and ignite gas and smoke otherwise escaping to the stack; to 20 provide means for maintaining the grate bars of a furnace at a relatively low temperature; to provide a grate bar structure having its front end located directly in the path of the entering air; and to provide 25 other improvements as will hereinafter appear.

In the accompanying drawings Fig. 1 represents a longitudinal, sectional elevation of a furnace showing a grate bar construction embodying one form of the present invention; Fig. 2 represents a section on line 2—2 of Fig. 1; Fig. 3 represents a detail in part section of a grate bar end; Fig. 4 represents a detail in section of the meeting ends of the 35 grate bar sections; Fig. 5 represents a transverse section of a grate bar embodying another form of the invention; and Fig. 6 represents a modified form of grate bar construction.

40 Referring to the drawings, a grate 10 embodying one form of the present invention is shown in Fig. 1 installed below the boiler 11 which is mounted as a part of a furnace having a combustion chamber 12, ash pit 13, a bridge wall 14, a firing opening 15, and a draft opening 16. The grate 10 is arranged to be supported at its ends respectively on the usual transverse grate supporting bars 17 and 18 while the central portion thereof is 45 carried by two spaced bars 19 which also extend transversely of the furnace, but at a substantially lower level than the bars 17 and 18.

The preferred form of grate bar embodying the present invention is formed of two sections 20 and 21 placed in end to end relation to form a complete bar extending lengthwise of the furnace. The front grate bar section 20 is formed with an upwardly curved neck 22 with walls terminating in a forward extension 23 arranged to seat upon 55 the supporting bar 17, the construction being such that the neck 22 lowers the body part of the bar considerably below what would be its level as determined by the bar 17. Also this lowered position of the grate bar brings 60 its forward end below the bar 17 so that it is directly in the path of the air entering by way of the opening 16. The extension 23 is provided with a laterally disposed lug 24 which properly spaces one bar from another. 65 At the opposite end of the bar section a lug 25 also laterally disposed is provided for spacing purposes having a depending lip 26 to engage one of the cross bars 19 to hold 70 the grate section in proper position. 75

The grate bar section 21, where it engages the other cross bar 19, has a laterally disposed lug 27 with a lip 28 hooked over the aforesaid bar 19 to properly support and position the end of the bar section 21. At 80 the opposite end of the section 21 there is an upwardly curved neck 30 having walls terminating in a head 31 supported on the bar 18 and having its face abutting the face of the bridge wall 14. In connection with 85 the head 31 it should be noted that its top edge 32 curves upwardly and rearwardly to form a slightly elevated rear fuel bed in close proximity to the top of the bridge wall, while the latter is formed as an upwardly and 90 rearwardly inclined surface 33 which merges into the edge 32 at its lower part. Thus the surface 33 and the grate bar edge 32 at its rear form a part of the same incline, one being a continuation of the other, whereby the 95 bridge wall top can be readily cleaned and clogging at the bridge throat of the combustion chamber prevented.

For maintaining the grate bars relatively cool and for supplying air in a preheated 100 state to the combustion chamber the sections of each grate bar are formed with a groove 34 extending throughout the length of each section and of a depth, width and shape to

form two relatively long, thin sides 35 which have the general effect of elongated fins exposed to the cooling air to conduct the heat away from the body of the grate bar and so 5 keep its temperature down. The two sections of each grate bar are maintained in end to end alinement by a lug 36 projecting laterally from the end of one section and in such a position as to enter the groove 34 of 10 the other section where it has a snug fit to prevent displacement of one section with respect to another.

In order to deliver the air, which is heated by its passage through the groove 34, to the 15 combustion chamber at the place where it most effectively promotes combustion, the head 31 on the section 21 is formed with a vertical slot 37 which communicates with the rear end of the groove 34 and thus provides 20 an outlet passage for discharging the air into the combustion chamber at substantially the entrance to the throat formed by the bridge wall 14. The effect of the heated air discharging at this location is to introduce 25 fresh oxygen into the smoke and gases leaving the combustion chamber so that a fresh mixture is formed which immediately ignites and completes the combustion of what would otherwise be wasted and discharged as 30 smoke.

In the form of the invention shown in Fig. 5 a grate bar 40 of sectional construction is provided generally similar to that already described except in this instance each of its 35 sections is subdivided on a vertical plane passing through its longitudinal axis into two complementary parts 42. These parts are provided on their meeting faces with spacing lugs 43 whereby the proper relative assemblage of the grate bar parts by fastening bolts 44 and 45 forms a complete unitary section having a longitudinally arranged slot 46 in its bottom portion. This construction provides an economical way to manufacture 40 the grate bar sections and gives very accurately fitting parts.

In some instances it may be desirable to regulate the amount of preheated air delivered through the passage or slot in the grate bar and to that end a damper or valve member 47 is pivoted as seen in Fig. 6 to two of the grate bars by means of depending brackets 48 and extends transversely across the grate below the neck 31. An arm 50 attached to the axis of the damper 47 transmits motion of an operating rod 51 which extends to an accessible point at the front of the furnace. By shifting the rod 51 the position of the damper 47 can be varied at will to proportion the amount of air delivered to the furnace in accordance with conditions.

From the foregoing it will be apparent 55 that a complete unitary grate bar construction has been provided whereby all the gases

are consumed and the discharge of smoke eliminated. Furthermore by forming the bars with a depressed central or body part an increased depth of fire box is obtained which gives additional burning area and 70 minimizes the escape of heat units to the stack. This depressed grate bar construction brings the inlet ends of the grate bar slots into the path of the entering draft air, and the latter is thereby caused to flow 75 straight through the slots, absorbing heat from the walls and finally passing upwardly through the rear heads to discharge into the chamber along the bridge wall line. This regulation of air, preheating and mixing, 80 contributes to a clinker free grate since it prevents the adherence of clinkers and provides a durable and readily cleaned grate structure. It should be noted also that the air passing along under the grate bars from 85 front to rear and discharging in a heated condition at the rear creates an extra draft which maintains a working circulation and produces an intense flame.

While only three forms are shown in 90 which this invention may be embodied, it is to be understood that the invention is not limited to any specific construction, but might be applied to various forms without departing from the spirit of the invention or 95 the scope of the appended claims.

Having thus described my invention, I claim:

1. In a furnace grate bar construction, an intermediate and end support bars for grate bars, arranged in spaced relation with the intermediate support substantially below the level of both end supports, a plurality of sectional grate bars positioned on said supports with the sections of each grate bar arranged in end to end abutting relation over the intermediate support, an upturned portion on each of the non-abutting ends of each grate bar section and extending above the top of the grate bar, said upturned portions being formed for seating engagement on said end supports substantially at the level of the top of the grate bar, flanges of uniform solid construction depending in parallel spaced relation from the opposite side edges of each 115 of said grate bar sections considerably below the tops thereof and defining a deep air passage groove continuous from end to end of the grate bar, one of the upturned end portions being formed with an air passageway 120 extending therethrough from the groove, and an interfitting lug on one abutting end of a grate bar section extending into the top of the groove in the abutting end of the adjacent grate bar section over said intermediate support and in spaced relation thereabove.

2. In a furnace grate bar construction, the combination of a support for the front end of a grate bar, a grate bar having a grate 130

surface and being formed with an upturned front end engaged with said support in such manner as to dispose the grate surface at the level of said support with the body of the bar extending considerably below that level, said body being formed with a deep bottom opening groove longitudinally of the

bar and open at the front end beneath said support.

Signed at Philadelphia, county of Philadelphia, State of Pennsylvania, this 20th day of April, 1925.

DENNIS MELLOR.
